Patented Sept. 25, 1917.

UNITED STATES PATENT OFFICE.

HERMAN ROSENZWEIG, OF NEW YORK, N. Y.

WINDOW SASH AND FRAME.

1,241,285.

Specification of Letters Patent. Patented Sept. 25, 1917.

Application filed September 22, 1916. Serial No. 121,632.

To all whom it may concern:

Be it known that I, HERMAN ROSENZWEIG, a citizen of the United States, and a resident of the city of New York, borough of 5 Manhattan, in the county and State of New York, have invented a new and Improved Window Sash and Frame, of which the following is a full, clear, and exact description.

10 Among the principal objects which the present invention has in view are: to simplify and strengthen the construction of window frames and sashes; to avoid air drafts in the window-closing members; to 15 facilitate the operation of window sashes; and to facilitate the cleaning of said sashes.

Drawings.

Figure 1 is a side view of a window having sashes and frames constructed and arranged in accordance with the present invention;

Fig. 2 is a detail view showing in perspective a fragment of window frame and 25 of a sash mounted therein, the sash being shown as pivoting on one of its guide members;

Fig. 3 is a cross section on an enlarged scale, the section being taken as on the line 30 3-3 in Fig. 1;

Fig. 4 is a detail view in perspective showing a lock strip with which sashes constructed in accordance with the present invention are provided;

35 Fig. 5 is a detail view of a clamping screw for moving the lock strips to engage or disengage the guide members, and for locking the same fixedly in correspondence therewith.

Description.

As seen in the drawings, the window sashes constructed and arranged in accordance with the present invention have stiles as 45 indicated by the numeral 10, constructed from a single piece of metal bent in the form as shown best in Fig. 3 of the drawings, to provide a seating channel 11 and a pocket 12 for a locking strip 13. The rails 14 of 50 the sash are constructed in a similar manner except that the pocket 12 is not formed therein.

The sashes are pivoted by a double-headed rivet 15 to a guide member 16. The member 16 has at one edge, a guide flange 17

formed by closely lapping the metal on itself. On the opposite edge, the member 16 has a guide flange 18, which in conjunction with a flange 19, forms a pocket 20, which in service registers with the pocket 12 and 60 is adapted to receive the strip 13 when the same is moved laterally from the pocket 12.

When the strip 13 is moved into the pocket 20, the sash is held in non-rotative relation to the member 16. The screw 21 65 which is threaded in a perforation formed in the strip 13, may now be manipulated to clamp the metal of the stile between the said strip 13 and the wing nut head 22 of the said screw. Each stile has two screws 70 having heads 22.

When it is desired to rock the sashes on their pivots 15, this is done by preliminarily releasing the screws 21, and thereby relieving the frictional clamp on the strip 13, 75 which permits the same to be retracted into the pocket 12 to free the pocket 20.

It will be seen that in the above-mentioned position, the sashes may be swung on their pivots irrespective of the position they 80 occupy in the frame. Of course it will be understood that the opposite sash is removed from interference with the frame which is to be pivoted. Attention is drawn to the fact that this arrangement permits 85 the upper sash to be opened to swing on its pivot while the lower sash is closed.

The frame has stiles 23 constructed of sheet metal which is bent to form in the face of the stile, two sets of grooves 24. 90 The grooves 24 are separated a distance approximately the thickness of the sashes and the width of the members 16, and are arranged to receive the flanges 17 and 18 of the members 16. By reason of the fact that 95 the grooves thus formed are disposed as shown, it is obvious that the tortuous passage between the surfaces of said grooves and the surfaces of the flanges 17 and 18, forms a wind or weather break. This function is 100 augmented by the hollow spaces 25 formed between the members 16 and the faces of the stiles 23. The establishment of a minor expansion chamber thus between the outside and inside pressures operates to check the 105 passage of the air through the first of the second groove. As the pressure on the exterior is fitful it does not gain admission to the inner grooves 24.

A similar effect to that above described 110

is performed by the strips 13 which bridge across the junction of the stiles 10 and members 16 to form a varying wind break therefor.

5 To cover the openings of the slots 26 formed in the stiles 10 for the screws 21, there are provided cover plates 27 which are permanently secured to the screws 21.

10

Claims.

1. The combination of a window frame having side stiles provided with narrow parallel vertical grooves, said grooves being disposed in pairs, the grooves of each pair 15 being separated a distance approximately equal to the thickness of the sash accommodated by said frame, the inner grooves of said pairs being adjacently disposed; guide members having side flanges fitting in 20 said grooves; sashes pivoted on said guide members to swing between said guide members; and means for holding said sashes and said guide members in fixed relation.

2. The combination of a window frame 25 having side stiles provided with narrow parallel vertical grooves, said grooves being disposed in pairs, the grooves of each pair being separated a distance approximately equal to the thickness of the sash accommodated by said frame, the inner grooves of 30 said pairs being adjacently disposed; guide

members having side flanges fitting in said grooves; sashes pivoted on said guide member to swing between said guide members; means for holding said sashes and said guide members in fixed relation; and movable flanges slidably mounted on said sashes, said flanges being adapted to close the joint between said sashes and said guide members to prevent the passage of air therebetween. 40

3. The combination of a window frame having side stiles provided with narrow parallel vertical grooves, said grooves being disposed in pairs, the members of each pair being spaced apart; guide members having flanges fitting said grooves to slide therein, the width of said flanges being greater than the depth of said grooves for forming between said flanges and the body of each of said members and the adjacent sash, expansion chambers for preventing the free passage of air between the sashes and frames; sashes pivoted on said guide members to swing between the same; and means for holding said sashes and guide members fixed in service relation. 50
